(57) **CLAIM**

The ornamental design for a head band wrap component, as shown and described.

DESCRIPTION

FIG. 1 is a facing, right side, and top perspective view of a head band wrap component, employing my design;

FIG. 2 is a facing view thereof;

FIG. 3 is left side elevational view thereof;

FIG. 4 is right side elevational view thereof;

FIG. 5 is a top plan view thereof;

FIG. 6 is bottomplan view thereof;

FIG. 7 is rear elevational view thereof;

FIG. 8 is a facing, right side, and top perspective view thereof shown with one type of use;

FIG. 9 is another facing, right side, and top perspective view thereof shown with another type of use; and,

FIG. 10 is yet another facing, right side, and top perspective view thereof with still another type of use.

The dotted lines represent environmental matter and form no part of the claimed design.
